AUGUSTUS M. WING, OF SPOKANE, WASHINGTON, ASSIGNOR OF ONE-HALF TO GRANT JOSEPH BOWMAN, OF SPOKANE, WASHINGTON.

LETTER AND NUMERAL RULE.

No. 861,151.

Specification of Letters Patent.

Patented July 23, 1907.

Application filed December 10, 1903. Serial No. 184,581.

To all whom it may concern:

Be it known that I, AUGUSTUS MONROE WING, a citizen of the United States, and a resident of Spokane, in the county of Spokane and State of Washington, have invented a new and Improved Letter and Numeral Rule, of which the following is a full, clear, and exact description.

The invention relates to drawing instruments, and its object is to provide a new and improved letter and numeral rule, which is very simple in construction, easily manipulated and more especially designed for conveniently and quickly forming numerals and letters of the alphabet, both capital and small letters, without requiring a skilled operator.

The invention consists of novel features and parts and combinations of the same, as will be more fully described hereinafter and then pointed out in the claims.

A practical embodiment of the invention is represented in the accompanying drawings forming a part of this specification, in which similar characters of reference indicate corresponding parts in all the views.

Figure 1 is a face view of the improvement, arranged for making block letters and numerals; Fig. 2 is a like view of a modified form of the improvement, arranged for making round letters and corresponding numerals; Fig. 3 is a face view, showing the improvement in the several positions required for forming the capital letter "K"; Fig. 4 is a similar view of the same, showing the various positions required for forming the capital letter "M"; Fig. 5 is a like view of the improvement, showing the two positions required for forming the small letter "a" in full block Gothic style; Fig. 6 is a like view of the improvement, showing the several positions required for forming the numeral "25". Fig. 7 shows on a reduced scale, a shank A² having a hook B at each end; and Fig. 8 illustrates on a reduced scale, a shank A³ having a block letter hook B at one end and a round letter hook B¹ at the other end.

The improved letter and numeral rule is preferably made from a transparent or translucent material, such as sheet celluloid or the like, but it may also be made of wood, cardboard or the like. The rule is made in the form of the letter "J", and consists of the shank A and the hook B extending integrally from one end of the shank A and of equal width. The extreme transverse width of the rule at the end provided with the hook is equal to the aggregate distance of one half of the height of the letter to be made plus one half of the width of the shank A, and the distance between the upturned portion of the hook and the shank is approximately equal to the width of the shank. As shown in Fig. 1, the shank A has its lower corners cut off, to adapt the rule more especially for forming block letters and correspondingly shaped numerals, and in the arrangement

illustrated in Fig. 2, the hook B¹ extends integrally from one end of the shank A¹ and is curved, so as to permit of using this rule for forming letters and numerals of the round type.

The shank A or A¹ is provided with dotted lines a and b, extending from one side to the other at right angles thereto, and the distance between these lines a and b indicates the height of the letter to be formed, it being understood that for different sized letters, the distance between the lines a and b increases or diminishes, and the width of the shank A and that of the hook B is correspondingly changed.

Near the upper end of the shank A are formed angular marking lines d and e, and a straight marking line f, arranged in the lower portion of the shank, and between this marking line f and the dotted line b is arranged an angular marking line g.

For forming the letters of the alphabet, except the letters "A", "K", "M", "V" and "W", the shank A and the hook B only are used, while for forming the said letters "A", "K", "M", "V" and "W" use is also made of the angular marking lines d, e and g. The distance from the marking line f to the bottom of the hook B represents the width of the letter, the distance mentioned also corresponding to the width of the hook. In making the letter B, for instance, the stem is first produced and then the hook B is extended sideways beyond the stem, until the line f coincides with the left hand line of the stem, thereby indicating the width of the letter without measuring the width by the transverse portion of the hook B. A marking line h is arranged on the hook B, and divides the hook equally, and it is used in measuring or cutting off the balance of the hook.

In making the letter S and round letters and numerals, the hook B¹ is in addition provided with a chord i, and end marking lines j and k are also arranged on the hook B¹, to form the proper endings for the round letters, as will be readily understood by reference to Fig. 6. The line j represents the point at which the hook begins to curve back towards the shank and is used to cut off the balance of the hook in making certain letters. The line k is merely a line for convenience in cutting off the balance of the hook in making modified letters.

In using the letter and numeral rule for forming letters, the heights thereof are laid off by the distance between the lines a and b, two parallel lines of this distance being drawn on the paper or other device on which the letters or words are to be formed. The operator now proceeds by using the shank A and the hook B, according to the configuration of the letter to be formed, special rules being laid down for facilitating the work, but it is evident that by the particular shape

given to the shank A and hook B and by the use of the angular marking lines above mentioned, any letter in the alphabet can be readily formed, without requiring much skill on the part of the operator, and correspondingly shaped numerals may also be formed by the use of the rule.

In making a letter for some alphabets, say the Roman, it is desirable to have a hook B at each end of the shank, and it may also be desirable to have a block 10 letter hook B, such as shown in Fig. 1, on one end of the shank A, and a round letter hook, such as shown in Fig. 2, on the other end of the same shank.

It will be understood that the angular marking lines *d, e, g*, are arranged at angles with respect to the shank, 15 corresponding to the angles which the base line of the letter to be formed makes with the inclined portions of said letters.

Having thus described my invention, I claim as new and desire to secure by Letters Patent:

20 1. A rule for forming letters, comprising a straight shank of even width, and a hook extending integrally from one end of the shank, the opposite sides of the hook being parallel with each other, and spaced apart a distance equal to the width of the shank, said shank having marking 25 lines each arranged at an angle with the shank, corresponding to the angle of the base line of the letter to be formed with the direction of length of the inclined portion of said letter.

2. A rule for forming letters, comprising a straight 30 shank of even width, having parallel sides and a hook extending integrally from one end of the shank, the shank being provided with angular marking lines for the purpose set forth, and with transverse space lines adjacent to each end thereof, the distance between the space lines corresponding to the height of the letters to be formed, the shank and hook being of substantially the same width throughout the extent of the rule.

3. A rule comprising a straight shank with parallel sides, and a hook extending integrally from one end of the 40 shank, the shank being provided with angular marking lines each arranged at an angle with the shank, corresponding to the angle of the base line of the letter to be formed, with the direction of length of the inclined por-

tion of said letter, and transverse space lines adjacent to each end thereof, the distance between the space lines corresponding to the height of the letter to be formed, and the said hook being provided with marking lines for the purpose set forth. 4

4. A rule for forming letters, comprising a shank of even width having space lines adjacent to each end thereof, and corresponding to the height of the letters to be formed, and a hook extending integrally from one end of the shank, the extreme width of the rule corresponding to the aggregate distance of one half of the length of the letter to be formed plus one half of the width of the shank. 5

5. A rule for forming letters comprising a shank of even width having angular marking lines and a hook extending integrally from one end of the shank, the extreme width of the rule corresponding to the aggregate distance of one half of the length of the letter to be formed plus one half of the width of the shank. 6

6. A rule for forming letters comprising a shank of even width, and a hook extending integrally from one end of the shank, the extreme width of the rule corresponding to the aggregate distance of one half of the length of the letter to be formed plus one half of the width of the shank, and a marking line on said shank at a point above the bottom of the hook corresponding to the extreme width of the rule. 7

7. A rule for forming letters comprising a shank of even width, having angular marking lines and transverse space lines indicating the height of the letter to be formed, and a hook extending integrally from one end of the shank, the extreme width of the rule corresponding to the aggregate distance of one half of the length of the letter plus one half of the width of the shank, and a marking line on said shank at a point above the bottom of the hook, corresponding to the outer width of the hook, and the said hook having marking lines as set forth. 7

8. A rule for forming letters comprising a shank of even width, and a hook extending integrally from one end of the shank, the extreme width of the rule corresponding to the aggregate distance of one half of the length of the letter plus one half of the width of the shank, the shank and hook having marking lines as set forth. 8

In testimony whereof I have signed my name to this specification in the presence of two subscribing witnesses.
